CLAIM

The ornamental design for fluid delivery system, as shown.

DESCRIPTION

FIG. 1 is a perspective view of the fluid delivery system.

FIG. 2 is a left side view of the fluid delivery system.

FIG. 3 is a right side view of the fluid delivery system.

FIG. 4 is a back view of the fluid delivery system.

FIG. 5 is a front view of the fluid delivery system.

FIG. 6 is a top view of the fluid delivery system; and,

FIG. 7 is a bottom view of the fluid delivery system.

The dotted lines in FIGS. 1-7 do not form any part of the claimed design for the fluid delivery system.
